UNITED STATES PATENT OFFICE

OTTO GERNBROSS, OF BERLIN-GRUNEWALD, AND KURT RÜLKE, OF CHARLOTTENBURG, GERMANY, ASSIGNEES, BY MESNE ASSIGNMENTS, TO KALI-CHEMIE A. G., OF BERLIN, GERMANY

DISINFECTANT, ANTISEPTIC, AND HEALING MEDIUM

No Drawing. Application filed March 9, 1925, Serial No. 14,275, and in Germany June 27, 1924.

By our application No. 274 filed on January 2, 1925 is described a disinfecting or antiseptic agent or remedy which is composed of disinfecting salts of heavy metals and of 5 thiocyanogen compounds that increase the action of the former.

Further experiments have shown that even organic disinfectants, by combination with thiocyanogen salts can also be activated in 10 such a way that their disinfecting or antiseptic and healing effects are very materially increased. The activating effect of the thiocyanogen compounds particularly shows itself to advantage more particularly in the presence of albuminous substances, mucilage and 15 the like.

As disinfecting or antiseptic media capable of being activated there come into consideration organic compounds of the most varied 20 kind, for example alcohols, such as ethyl alcohol, isopropyl alcohol and the like, compounds containing phenolic bodies and their derivatives, such as phenol, sodium chloro- 25 metacresol, guaiacol and hydroxyquinoline, aldehydes, such as formaldehyde, heterocyclic 30 compounds such as 1-phenyl-2, 3-dimethyl-5-pyrazolon and quinine, and terpenes and their derivatives, such for example as terpineol, oil of cloves and the like.

As activating compounds there come into 35 consideration those of the light metals, particularly those of the alkali metals, including ammonium, and of the alkaline earth metals, including magnesium. The quantity of the thiocyanogen compounds to be added may 40 vary within wide limits. It may under some circumstances be very high in relation to the quantity of the organic body to be activated. The additions of alkali metal thiocyanate and the like requisite for obtaining the best results are settled according to the nature of the medium to be activated, according to the concentration of the solutions, mixtures, triturations and the like to be employed, according 45

to the object in view, and so forth. When employing the disinfecting medium in the presence of albumin the addition of alkali metal thiocyanate and the like is preferably effected in such quantities that the utmost 50 possible steeping and liquefying action is ex-

erted upon the albumin and related substances.

For the purpose of manufacturing the disinfecting medium one may for example proceed by bringing together the initial materials by converting sodium chloro-metacresol and potassium thiocyanate into an aqueous solution. One may for example proceed by introducing the components together or successively into a solvent, or by first preparing 55 mixtures that contain the constituents in suitable quantities, and then converting these into such suitable forms as are desired for use, such as solutions, suspensions, salves, pastes, sticks or the like. One may also for example proceed by first grinding down one component for example with an ointment base, and then adding the other. In given cases one may also combine a number of disinfectants with one another, and activate the 60 mixture thereof by the aid of thiocyanogen compounds, or combine a number of thiocyanogen compounds with one or more disinfecting media. 65

Other effective or ineffective substances 70 may also be incorporated with the disinfecting, antiseptic and healing media manufactured according to the invention, particularly such as are usual in the manufacture of 75 remedies and disinfectants, such for example as saponin, starch, dextrine and the like.

Besides the increases in effectiveness as regards disinfectant and antiseptic actions obtainable owing to the presence of thiocyanogen compounds, the invention also presents 80 other advantages in other directions. Thus the combination of expensive disinfectants with cheap thiocyanogen compounds involves a cheapening, inasmuch as while employing smaller quantities of the dearer organic compounds, equal and even enhanced 85 results can be obtained. 90

Examples

(1) 1 part of phenol is mixed with 4 parts 95 of ammonium thiocyanate and 200 parts of water.

(2) 1 part of 1-phenyl-2, 3-dimethyl-5-pyrazolon with 2 parts of potassium thiocyanate are finely powdered and mixed to- 100

gether. The product is employed in the form of tablets, to which also taste correctives may be added.

(3) $2\frac{1}{2}$ parts of 40 per cent formaldehyde are introduced into an aqueous solution of 8 parts of KCNS the whole made up to 200 cubic centimetres with water, to which perfumes and flavouring substances may be added, and diluted with water before use if desired.

It is already known that by means of alkali metal thiocyanates and alkaline earth metal thiocyanates gelatine can be protected against the tendency of formaldehyde to cause flocculent precipitation, and can thereby be kept in solution. In the case of this process the thiocyanogen salt is the protecting means for the gelatine. The addition must therefore be effected in the quantities requisite for obtaining this protective action. Accordingly the present invention is based on the new discovery that thiocyanogen salts are capable of materially enhancing the disinfecting and antiseptic action of organic disinfectants. The addition has therefore to be made in the case of the present invention in such quantities that the utmost possible increase in effect is obtained. The combination of thiocyanogen salt, gelatine and formaldehyde is excluded from the present invention.

What we claim is:—

1. A disinfecting, antiseptic and healing medium comprising at least one organic disinfecting compound and at least one thiocyanogen compound adapted to enhance the action of said organic disinfecting compounds.

2. A disinfecting, antiseptic and healing medium comprising at least one organic disinfecting compound, at least one thiocyanogen compound adapted to enhance the action of said organic disinfecting compounds, and at least one substance having the property of reducing the surface tension of the medium.

3. A disinfecting, antiseptic and healing medium comprising at least one organic disinfecting compound and at least one thiocyanogen compound of a light metal.

4. A disinfecting, antiseptic and healing medium comprising at least one organic disinfecting compound and at least one alkali metal thiocyanogen compound.

In testimony whereof we have signed our names to this specification.

55 OTTO GERNGROSS.
KURT RÜLKE.
